(57) **CLAIM**

The ornamental design for a chemical injection tip, as shown and described.

DESCRIPTION

FIG. 1 is a front perspective view of a chemical injection tip, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dot-dash broken line(s) define the bounds of the claimed design and form no part thereof. The dash-dash broken line portion of the figures is included to show unclaimed subject matter only and forms no part of the claimed design.

1 Claim, 4 Drawing Sheets
